UNITED STATES PATENT OFFICE.

LOENDER C. EMERSON, OF GRAFTON, MASSACHUSETTS, ASSIGNOR TO THE MERRICK SEWING MACHINE COMPANY, OF BOSTON, MASSACHUSETTS.

EYELETING-MACHINE.

SPECIFICATION forming part of Letters Patent No. 644,797, dated March 6, 1900.

Application filed November 4, 1895. Renewed May 27, 1899. Serial No. 718,534. (No model.)

To all whom it may concern:

Be it known that I, LOENDER C. EMERSON, of North Grafton, in the county of Worcester and State of Massachusetts, have invented 5 certain new and useful Improvements in Eyeletting-Machines, of which the following is a specification.

In certain styles of laced boots and shoes it is customary to set over a number of the eyelets at the lower ends of the rows which are fastened in the upper, giving the rows an outward curved or spread appearance.

It is the object of this invention to provide means in an eyeletting-machine whereby the 15 setting over of these eyelets in the desired manner is insured.

In furtherance of the above-stated object I arrange a movable guide or gage for the work and make provision for moving the same 20 at the proper time and in the proper manner to dispose the work for receiving the set-over eyelets.

A mechanism embodying the invention is described hereinafter and illustrated in the 25 accompanying drawings, which form part of this specification.

Figure 1 shows a side elevation of a portion of an eyeletting-machine to which the invention is applied. Fig. 2 shows a front elevation. Fig. 3 shows a top plan view of the work-supporting table and parts connected therewith. Fig. 4 shows a side elevation of 30 a portion of the machine from the same side as Fig. 1, certain parts being removed. Fig. 35 5 shows a section on line 5 5 of Fig. 4. Fig. 6 shows a section on line 6 6 of Fig. 5.

The general construction of the eyeletting-machine is not changed from that ordinarily employed in machines of this character, and 40 it will not therefore be necessary to enter into a detailed description of the same. An enumeration of a number of the principal parts will suffice.

The letter *a* designates the work-supporting bed or table, which is slotted, as at *a'*, to accommodate the punching and upsetting devices.

b designates the perforating-die, and *c* and *d* designate the usual carriers for the upsetting-dies, the carrier *d* being affixed to a ver-

tical rod *d'*, which is reciprocated vertically in fixed guides *d* *d'* on the frame of the machine.

On the upper side of the table *a* is arranged a guide or gage *e*, formed to bear on the edge of a boot or shoe upper supported on the table, the said gage being adjustable toward and from the point where the setting-dies coact to determine the distance of the eyelets from the edge of the upper. It will be apparent that as long as one position of said guide or gage obtains the eyelets will all be inserted the same distance from the edge of the upper, said guide or gage being adjacent to the slot *a'*, and that a change in the position of the gage will effect a change in the distance from the edge of the upper to the place of insertion of the eyelet. Therefore by moving the gage laterally with relation to the coacting point of the sets and the edge of the upper receiving the eyelets any desired distance between the edge of the upper and the place of insertion of the eyelets can be had. Hence by supplying suitable means to move the gage the object primarily stated can be accomplished. The means here shown are as follows:

A vertical stud or shaft *f* is journaled in a bearing in a block *f'*, affixed to the frame of the machine. To the upper end of said shaft is affixed a crank-arm *f''*, containing a slot *f'''*. Said arm is connected by a link *f'''* with a slide *g*, which is movable on the under side of the table *a* and is engaged therewith by means of plates *g' g''*, movable in guides in the upper side of the table and connected through slots 85 in the table with the slide *g* by screws *g''' g''''*. The gage *e* is secured to the plate *g''* by the screw *g''''* and is therefore movable with the slide *g*. It will be seen, therefore, that a rotation of the shaft *f* will, through the crank-arm *f''*, link *f''''*, and slide *g*, move the gage *e* toward or from the point where the setting-dies coact. Means are provided for rotating said shaft step by step in either direction by the power of the machine, and consequently 90 automatically, said means represented by a ratchet-plate *h*, affixed to the shaft *f* and provided with two series of ratchet-teeth *h' h''*, a carrier *i*, which is movable toward and from the shaft *f* and carries two pawls *i' i''*, adapted, 100

respectively, to engage the ratchet-teeth h' h^2 , and means for moving the pawl-carrier toward and from the shaft f .

The means for actuating the pawl-carrier during the movement of the setting devices to set an eyelet is represented by an arm j , pivoted at j' to a fixed stud j^2 and bearing loosely on the pawl-carrier i , said arm being arranged so that a lug or projection d^4 on the setting-die carrier d will strike a roll j^3 on the lower end of the arm at each descent of the die-carrier, and thus move the pawl-carrier toward the shaft f . The pawl-carrier is moved away from the shaft f by a spring j^4 . It follows, therefore, that the pawl-carrier is moved toward the shaft f by each downward movement of the setting-die carrier d and is moved away from said shaft during each upward movement of the said die-carrier.

20 Provision is made for making the pawl i' operative and the pawl i^2 at the same time inoperative, and vice versa, said pawls and the accompanying ratchet-teeth being so arranged that when one pawl is operative it is caused by the described movements of the pawl-carrier to rotate the shaft f step by step in one direction, whereas when the other pawl is operative it will rotate the said shaft step by step in the opposite direction, said pawl and 25 the pawl-carrier controlling suitable actuating mechanism for the ratchet-plate. To this end I pivot at k^3 to a downwardly-projecting ear on the pawl-carrier i a lever k , under the control of the operator, it having at 30 opposite sides of its pivot two pins k' k^2 , projecting upwardly through holes in the pawl-carrier and having their upper ends beveled, as shown in Fig. 6. The lever k is adapted to be moved on its pivot by the operator, one 35 of its ends being extended to form a handle. When the handle end is elevated, the pin k^2 is raised, as shown in Figs. 4 and 6. Its beveled end is caused to move the pawl i' outwardly, making it inoperative, as shown in 40 Fig. 5, the pin k' being at the same time depressed, so that it releases the pawl i^2 and permits its engagement with the ratchet-teeth h^2 by means of the spring i^4 . It will be seen, therefore, that the operator can cause a step-by-step movement of the shaft f and gage e in 45 either direction by suitably adjusting the lever k .

The operation of the machine with reference to my improved attachment is or may be 50 as follows: The gage e being adjusted at the maximum distance from the eyelet-setting dies and the lever k adjusted to cause the step-by-step movement of the gage toward the setting-dies, the machine is set in operation as usual, the first eyelet being set with the gage in its maximum-distance adjustment. When the setting-die carrier d descends after setting the first eyelet, the lug d^4 moves the pawl-carrier, thus moving the gage 55 one step nearer the setting-dies through the described intermediate mechanism. When the setting-die carrier rises, the next eyelet

is set and the pawl-carrier is retracted by its spring, and so on, the gage being moved inwardly one step after the setting of each eyelet, the number of steps being determined by the number of ratchet-teeth. After the inward step-by-step movement of the gage has been completed the machine may continue to operate with the gage at the minimum distance from the setting-dies. After one row of eyelets has been set in this way the setting of the row in the next piece may commence at the upper end, the gage remaining at its minimum-distance adjustment, the setting 75 continuing until the point of spreading is reached, when the operator by moving the lever k causes the gage to recede step by step from the setting-dies, thus causing the lower eyelets to be set at gradually-increasing distances from the edge. The slot f^3 in the crank-arm f^2 enables the maximum distance of the gage from the setting-dies to be increased or diminished to vary the spreading of the eyelets, the link f^4 being connected 80 with the said crank-arm by a stud f^5 , which is adjustable in said slot. Hence by adjusting the said stud the operator may increase 85 or diminish the spread of the eyelets.

I do not limit myself to the described details of mechanism for giving the gage a step-by-step movement to vary the distance of successive eyelets from the edge of the piece in which they are inserted and may use any suitable means for giving the gage such movement without departing from the spirit of my invention.

I claim—

1. In an eyeleting-machine, an edge-gage for the work, and means for moving said edge-gage step by step to vary the location of successive eyelets from the edge of the work.

2. In an eyeleting-machine, the combination of a movable edge-gage for the work, a shaft journaled in a fixed bearing on the frame of the machine and provided with a crank-arm connected with the gage, and means for rotating said shaft step by step.

3. In an eyeleting-machine, the combination of a movable edge-gage for the work, a shaft journaled in a fixed bearing on the frame of the machine and provided with a crank-arm connected with the gage, means for rotating said shaft step by step, and means for reversing the direction of rotation of the shaft.

4. In an eyeleting-machine, a movable edge-gage for the work, intermittently-operating means for moving said gage progressively step by step to determine the location of the eyelets at graduating distances from the edge of the work, and means for varying the maximum distance of the gage from the setting-dies.

5. In an eyeleting-machine, setting devices, a movable edge-gage for the work, and means for moving said edge-gage automatically with relation to the said setting devices to determine the position of successive eyelets from the edge of the work.

6. In an eyeleting-machine, the following instrumentalities, viz: a slotted work-support, setting devices working in said slot, an edge-gage at the surface of said work-support, and means to change the position automatically of said edge-gage with relation to the coacting point of the sets whereby successive eyelets may be set at varying distances from the edge of the material.

10 7. In an eyeleting-machine, a work-support, a movable edge-gage, a connected arm, a plate provided at opposite sides of its center of motion with ratchet-teeth, connections between said arm and plate, actuating means to engage either of said sets of ratchet-teeth, means under the control of the operator to determine which set of said teeth shall be operated, and means to start said actuating means in motion at one operation of the machine in 20 setting an eyelet that said actuating means may between one and the next setting operation of the machine move the edge-gage automatically to vary the distance of successive eyelets from the edge of the work.

25 8. In an eyeleting-machine, a work-support, an edge-gage, a slotted arm, a plate having a plurality of ratchet-teeth at opposite sides of the center of motion, and actuating means coöoperating with said teeth to move 30 said arm and edge-gage automatically to vary the distance from the edge of the material of one and the next eyelet to be set.

9. A slotted work-support having an attached edge-gage and a presser-foot, and a top 35 and a bottom set, combined with a shaft, connections between said shaft and said work-support, a ratchet-plate attached to said shaft, and means to actuate said ratchet-plate inter-

mittently step by step in one and then in an opposite direction to thereby enable the eyelets to be set in the two pieces of a boot or shoe back from the edges of the eyelet-pieces at variable distances, substantially as described.

10 10. In an eyeleting-machine, the following instrumentalities, viz: a top and bottom set, means to actuate them, a slotted work-support having an edge-gage, automatic means to gradually move the work-support with its attached edge-gage laterally at the proper times with relation to said top and bottom set to thereby position the work resting on the said work-support with its edge against said edge-gage that eyelets may be set at any desired distance back from the edge of the eyelet-piece in which the eyelets are being set, substantially as described.

11. An eyeleting-machine containing the following instrumentalities, viz: a top set, a bottom set, means to actuate them, a slotted work-support having an edge-gage, and automatic means for gradually changing the relative position of said top and bottom sets and work-support and edge-gage to enable eyelets to be set at varying distances back from the edge of an eyelet-piece laid on said work-support, substantially as described.

In testimony whereof I have signed my name to this specification, in the presence of two subscribing witnesses, this 2d day of November, A D. 1895.
